B. P. Learned and
 Geo. N. Thatcher assignees of
 Reuben S. Blanchard of Albany N. Y.
 Letters Patent. No. 307. Dated August 13. 1850.

The Schedule referred to in these Letters Patent and making part of the same.

To all whom it may concern:

Be it known that I, Reuben S. Blanchard, of the City & County of Albany in the State of New York have invented or produced a new design or figure for an ornament to cast iron stoves to be formed on the plates of such stoves in casting the same & I do hereby declare that the following is a full and exact description of the same.

Fig. 1. in the drawings represents one half of the side plate and Fig. 2. one half of the end plate: the other halves corresponding.

In Fig. 1. the parts of the drawing above the line A B and that below the line C D are not parts of the side plate or of the design but are merely introduced to show the position of this plate when the stove is put together.

The ornament is composed of leaves and vines: and is all in relief, except the notched border seen on the edge of the side plate Fig. 1. and shaded. Fig. 3. is the general outline (without regard to the ornaments) of a horizontal section of Fig. 1. Fig. 4. is a similar outline of a perpendicular section of Fig. 2. or of the side plate (that is the part between A B and C D) in Fig. 1.

The oblong shaded spots of the curve at the bottom of the side plate denote parts of the ornament which are not in relief, but are slightly depressed.

What I claim as my invention and desire to have secured by Letters Patent is the combinations of leaves vines curves and other ornaments as represented in the annexed drawings and herein described as a design for cast iron stove plates making part of a cast iron stove.

Dated Albany July 12. 1850.
